MAGNETIC MACHINE FOR OPERATING ON BOLTS, NUTS, AND THE LIKE

Application filed December 31, 1925. Serial No. 78,508.

My present invention is shown as embodied in an automatic machine for screwing nuts on bolts, but it involves several entirely novel combinations of elements capable of use in other relations.

One feature of the invention is a magnetic holder for bolts in which bolts are non-positively but securely held, preferably so that they may be rotated or moved lengthwise for 10 various purposes without displacement. A novel embodiment is where a plurality of the bolt holders are formed in the periphery of a turret and there is a single magnetic field energizing all of the bolt holders and the 15 magnetic field is closed through the shanks of the bolts when in position on the holder. The field is strong enough so that bolts fed are automatically pulled into the holders at 20 high speed by the power of the magnet, thus making it practical to operate at high speed with the bolts presented in proximity to the periphery of the turret by the ordinary inclined guideway of the type commonly employed for feeding nuts and bolts. Another 25 feature is making the peripheral poles of the magnet vertically adjustable for various lengths of bolts, also the magnetic bolt holder elements removable so that the periphery may be equipped with different bolt holding 30 notches to accommodate bolts of different diameter.

Another feature of the invention is a magnetic nut holder which is revolved at high speed. Like the bolt holder, it has the advantage of pulling into position thereon, nuts fed in proximity thereto. The nut supporting element is a plane, preferably horizontal, circular surface, the area of which comprises two semi-circular poles of a magnet, the poles 40 being separated by a relatively thin strip of non-magnetic material, preferably brass. The remarkable, and indeed phenomenal, feature of this construction is, that the nut attracted to and resting on this surface, rotating at high speed, is not thrown off by centrifugal force, but, on the contrary, is instantly, automatically and perfectly centered on said surface. This is primarily because it tends 45 to bridge the poles that form part of the magnetic circuit. It engages this surface firmly,

both by reason of its own weight and by reason of the magnetic attraction. As a result, it quickly acquires the same speed of rotation as the magnet and then, being itself an annulus, it becomes further stabilized by centrifugal force. 55

The bolts being held in the magnetic holders on the turret clutch are indexed into registry with the center of the magnetic nut holder and screwing on the nut requires only endwise feed of the bolt while preventing rotation thereof. 60

An important feature of this combination is that no feed mechanism is required for the nuts, these being supplied through the usual inclined guideway down which they slide. Novel holding back mechanism is employed whereby the nuts are freed, one at a time, for the magnetic transfer to the nut holding 65 magnet. This holding back mechanism is an escapement operated only by a nut which has been screwed on the end of a bolt. Hence, if any imperfection causes failure of threading of the nut on the bolt, such nut remains on the chuck for threading on the next following 70 bolt, because the escapement does not operate to release a second nut. 75

While I have shown the bolt holding turret or chuck as used only in combination with the nut applying chuck, it is obvious it can be used in combination with a bolt pointer or a nut threader; also it affords a very desirable means for feeding bolts or the like, one by one, to or from any other desired mechanism, as, for instance, a threader. 80 85

The above and other features of my invention may be more readily understood from the following description in connection with the accompanying drawings, in which 90

Fig. 1 is a top plan view of an embodiment of the invention, in which the screwing of nuts onto bolts is the only operation to be performed; 95

Fig. 2 is a longitudinal section on the broken dotted line 2—2, Fig. 1;

Fig. 3 is a plan view of the bolt holding turret;

Fig. 4 is a vertical axial section of the same on the line 4—4, Fig. 3;

Fig. 5 is a detail perspective showing the 100

arrangement of removable bolt holding pole pieces of the turret;

Fig. 6 is a plan view of the magnetic nut holder;

Fig. 7 is an enlarged side elevation of the same, similar to the showing in Fig. 2, except that parts of the interior construction of the magnet are indicated in axial section;

Fig. 8 is a horizontal section on the line 8—8, Fig. 2; and

Fig. 9 is a detail view on the line 9—9, Fig. 1.

In Fig. 1, the assembly is shown as comprising a suitable supporting table, A, above which is supported the bolt holding turret, B, in operative relation to the nut holding magnet chuck, C, the bolt supplying means being indicated at D and the nut supplying means at E.

As shown in Fig. 2, the bolt holding turret is mounted on vertical shaft, 1, journaled in support A.

As shown in Figs. 3, 4 and 5, the assembly comprises a sleeve member, 3, secured to shaft 1 by spline or key, 4, and formed at the lower end with a horizontal annular head, 5, which may be supported on ball bearings, 2. Mounted on this sleeve, 3, is the hub, 6, of a shell, 7, having at its lower end an external annular head or flange, 8. The hub, 6, is slidably but non-rotatably secured on sleeve 3 by spline 9 and locked in any desired vertical position by set screw 12. These parts are of magnetic material and constitute a magnetic circuit for magnetizing coil 10 which surrounds sleeve 3 and is supported by head 5. The annular heads or flanges, 5 and 8, carry similar pole pieces, 13, which form the extreme terminals or poles of the magnetic circuit which is completed by the shanks of the bolts α when the latter are in position. The vertical distance between upper and lower cooperating pole pieces may be adjusted for longer and shorter bolts by loosening the locking screw 12 and sliding hub 6 up or down on the cooperating sleeve member 3.

The pole pieces are made removable and replaceable to suit the diameters of the bolts used, yet are maintained functionally integral parts of the magnetic circuit by the construction shown in detail perspective in Fig. 5. This figure, in connection with Figs. 3 and 4, makes it clear that the flange or head, 8, has the bolt holding elements, 13, clamped against the lower face thereof by dogs or clamping members, 14, secured by screws, 15.

The outer ends of members 13 are formed with notches adapted to fit the bolts to be used, the rear face, 13^a, being substantially radial to afford a square backing for the bolt when in position and the forward face, 13^b, being inclined outward in the direction of rotation to permit the bolt to approach its seat diagonally instead of limiting this movement to a strictly radial one. The holding

pole pieces, 13, are secured against tangential or skewing displacement in the plane of the head by radial guideways which are formed by adjacent edges of the quadrant segment plates, 16, which are of magnetic material and similarly shaped plates, 17, which are of brass or other non-magnetic material, the iron and brass segments being secured together by screws 18 and both secured to head 8 by screws 19.

The non-magnetic segment, 17, projects a substantial distance beyond the periphery of the magnetic segment, 16, so as to space the bolts away from the head, preventing undue attraction and sticking thereof until approach of the notched magnetic holders, 13. The segments, 16, 17, afford guideways which do not have to be changed when smaller bolts are used, the widths of all sets of pole pieces, 13, being the same, only the size of the notches being different.

Current may be supplied to coil 10 in any desired way, as, for instance, by contact rings 19, 20, supported in insulation, 21, on the lower face of lower head, 5, cooperating stationary brushes, as 22, 23, being supported in any desired way on table A. One of the rings is of course wired to one end of magnet coil 10 and the other to the other end of said coil.

As shown in Figs. 6 and 7, the nut holding chuck C comprises a magnetic disc-like member, 25, supporting magnet windings, 26, 27, for the respective legs of the magnet, the latter comprising core pieces, 28, 28, secured to 25 by screw 29 and terminating in pole pieces, 30, 31, having closely confronting pole surfaces, 32, 33, separated by brass or other non-magnetic material, 34. These pole pieces and intervening non-magnetic material present a horizontal circular nut holding surface, 35, exposed above the top of support A which at this point is formed with an inserted brass plate, 36, because too close approach of iron to the poles would shunt too much of the magnetic circuit, around through other parts of the machine.

The above described magnet of the nut chuck is mounted upon stud shaft, 40, which is provided with a screw thread portion, 41, screwing into the above described magnetic disc or yoke member, 25. The shaft, 40, has a collar, 41^a, resting upon pole bearing, 42, on the upper end of the journal 43, in which shaft 40 rotates. The journal 43 is carried by yoke 44 secured to the under surface of support A by bolts 45.

Current for energizing coils 26, 27, is supplied in any desired way, as through conducting rings 46, 47, embedded in insulating material 48, on the rotating parts 40, 25 and contacting with stationary bushes 49, 50 in insulation support 51 carried by yoke 44.

The bolt supply means, D, comprises the usual inclined guides 60, 60, engaging the

heads of the bolts α with the shanks running down between the guides. The guides may be adjustably supported as by stud screws 61, 61 on one side and 62, 62 on the other side 5 engaging an inverted U-shaped support, 63, secured by bolts 64 to the table A. Bolts are supplied in continuous train either by hand or by well known automatic hopper mechanism commonly employed for this 10 purpose. Passing down the guideway by gravity in a continuous train, they are presented to the magnetic bolt holding turret as indicated in Fig. 2. They are prevented from falling off the guideway by engagement with the above described brass guard segments, 17, which project around the periphery of the turret, flush with the ends of the bolt engaging notches. When a notch comes opposite a bolt, the latter is immediately pulled into the notch by magnetic attraction, completing the magnetic circuit between the upper and lower pairs of notch members. While this action is usually certain and accurate enough for all practical 20 purposes, I may employ a pusher finger, 65, on a slide, 66, mounted in guides 67 vertically adjustable in a vertical supporting plate, 68, secured to the table A by bolts 69. The plate 68 has vertical slots, 70, in which 25 the clamping bolts 71 secure the guide 67 at any desired elevation. The elevation is preferably such as will bring the pusher into engagement with the bolt about midway between the upper and lower holding notches. 30 The slide is non-positively urged towards the bolt by spring, 73, its forward movement being adjustably limited by the bolt, 74, the head of which contacts with the rear face of guide 67. The slide is retracted once for 35 every indexing movement of the turret by positive means such as a roller, 79, engaging a cam, 79^a, rotating with the drive mechanism which will be described below. 40

On the other side of the guideway is a 45 similar construction of support, 68^a, slide, 66^a, retracting spring, 73^a, screw stop, 74^a, etc., but in this case there is no retracting means, the end of the pusher being formed with a cam surface, 89, slightly overlapping 50 the path of movement of the outermost portion of the bolt shank when it is properly positioned in the holder 13. The purpose of this is to yieldingly wipe the bolt and press it backward into firm engagement with the 55 bottom of the notch.

The nut supplying means, E, is shown as comprising an inclined guide-trough, 80, adapted to fit the smaller diameters of the nuts. The nuts slide down the trough and 60 a considerable number of them are maintained in train so that the lowermost nut may move promptly by gravity pressure when the release mechanism operates. At the lower end of the trough 80 is an automatic 65 escapement whereby the lowermost nut is freed and the train of the nuts in the rear therof held back. A stop, 81, carried by a lever arm, 82, mounted to oscillate horizontally on vertical pivot, 83, is yieldingly maintained in the nut stopping position by spring, 84. Projecting beyond the lever arm, 82, is a contact member, 85, in the path of travel of the nuts when they are screwed on the bolts and carried around by the turret. There is a 70 spring pressed clamping pin, 86, on the opposite side of the trough, normally engaging with the next nut of the series and preventing pressure thereof on the last nut which is in contact with dog 81, but this clamping pin is normally held out of engagement with the 75 second nut by a stud, 87, adjustably secured in a bracket, 88, on the lever arm 82. Therefore, when a nut screwed on a bolt in the 80 turret engages 85 and withdraws stop 81, the pin 86 is simultaneously released by retreat of stud 87, thereby permitting it to clamp the second nut before the dog 81 completely releases the last nut. As soon as dog 81 has been carried clear of the last nut, it is drawn automatically onto the chuck surface, 35, of the 85 rotating magnet and is automatically surrendered as described above. As soon as the contact member 85 is freed of engagement with the nut, the spring snaps stop 81 back into position and simultaneously retracts clamping pin 86, thus releasing the train of 90 nuts and instantly feeding another nut against stop 81. Obviously, the escapement will not work unless a nut has been screwed onto the bolt. Just beyond the nut feeding and supplying mechanism is arranged a stripper guideway, 90, located in the path of the bolt and operating to strip the same radially out of the notch of holder 13. 95

Driving the above described parts is simplified by reason of the fact that the bolt and nut magnets operate as substitutes for bolt and nut transfer mechanisms. The means here employed will be evident from Figs. 2 and 8. An important feature is the combination with the non-positive magnetic bolt holder of indexing mechanism of a type peculiarly adapted to start and stop the indexing movement as gradually as possible in order that this movement may be accomplished at high speed without throwing off the bolts from the magnet surface, by shock combined with centrifugal force. A suitable, well known mechanism which I have selected for this novel combination is the Geneva stop shown 105 more clearly in Fig. 8. The shaft 1, rotating the bolt holder B, is intermittently driven through rotor 100, having slots 101 engaged by roller 102 eccentrically located on rotor 103 on shaft 1^a. On the rotor 100, between 110 slots 101, are true cylinder surfaces, 104, adapted to engage the cylinder surface 105, which is integral with rotor 103. The latter surface is broken by a re-entrance surface 115 120 125 130 135 140 145 150 155 160 165 170 175 180 185 190 195 200 205 210 215 220 225 230 235 240 245 250 255 260 265 270 275 280 285 290 roller 102, so that the slot ends of rotor 100 may have clearance when the rotor 102 engages one of the slots. As will be evident from the drawing, slots 101 are tangential to the orbit of roller 102 and are at right angles to each other so that shaft 1 is rotated through a quadrant during the period of engagement of roller 102 with each of the four slots. The index position of the bolt holders is of course midway between the driving slots 101, so that they are held stationary during three-quarters of a revolution of 103, because one of the cylindrical segments, 104, will be accurately fitting the cylinder 105 and therefore holding shaft 1 in the index position.

Shaft 1^a may be driven at desired constant speed through beveled gear 107, by pinion 108 on shaft 109, supported in bearing 110. If the pusher finger 65 is used, this shaft 1^a will also carry the cam 79^a for contact with the roller 79, to retract the pusher.

While the nut holder C does not have to be actually synchronized with the rest of the driving mechanism, it is obviously desirable to have the speed at least sufficient to screw the nut onto the bolt during the time that the bolt holder is stationary in its index position, and as it is often possible to speed up the whole mechanism, I have preferred to drive the nut holder from a large gear, 111, on shaft 1^a, intermediate gear 112 on stud shaft 113 and pinion 114 on the nut holder shaft 40. By using the intermediate gear 112, the direction of rotation of the nut is right-hand for screwing onto the bolt. The multiplying ratio of these gears may be anything desired, but I have found the ratio shown practically satisfactory when the machine is driven at a speed for nutting, say, 70 or more bolts per minute.

From the above, the operation of the device will be obvious. A supply of bolts is maintained on the slides at D, either by hand or well-known automatic machinery. A supply of nuts is similarly maintained in trough 80. The drive shaft 109 is rotated at desired speed. The roller 102 of the Geneva stop engages a slot, 101, every revolution, rotates it 90° and leaves it locked. Gear 111 rotates with the driving member of the Geneva stop and causes high speed rotation of the nut holder through the multiplying gears 112, 114. Whenever the notches of the magnetic bolt holders 13 come opposite the bolt, the bolt is instantly pulled into the notch and bridges the magnetic circuit between the upper and lower poles. If the pusher is used, the spring 73 will cause it to follow up the bolt with a regulated pressure assisting in perfecting its seat in the notches. This is hardly necessary, however, because the next indexing movement will carry the bolt past the cam wiper surface 89, which insures firm engagement of the bolt shank with the radial surface 12^a of the notch. In the second posi-

tion, nothing is being done with the bolt, but it is obvious that any desired operation may be performed on it while in this position. As shown, however, nothing happens until the next indexing movement, which brings the bolt to the position shown at x', where the bolt is moved axially downward and held from rotation, preferably by an automatically acting wrench, indicated in dotted lines at 116, although this operation could be performed by hand if desired. Here the bolt, x', finds a nut properly centered and rotating at high speed in such a direction that the nut is instantly screwed onto the bolt. The next indexing movement brings the nut carried by the bolt into engagement with the escapement member 85, releasing another nut while holding back the supply in the trough 80, the free nut being instantly drawn to the magnetic nut chuck while the remainder of the indexing movement carries the nutted bolt by the stripper guides 90, leaving the notch empty for the next indexing movement to the bolts of supplying mechanism.

The nut chuck could be located at the fourth index position, the stripper being between it and the first or bolt supplying position, leaving the second and third positions available for any desired operation by other tools.

It will be noted further with respect to the turret to the periphery of which the bolts are held by magnetism, that there is advantage in having four or more of the bolt holders with a correspondingly large number of indexing positions, even though operation on the bolt is to be performed only in one of the index positions. The advantage is that each indexing step carries the bolt through a smaller angle, thus developing less centrifugal force for a given rate of nutting and indexing operations. For instance, if the turret had but two diametrically opposite bolt holding notches, the turret would be indexed a full-half revolution, or 180°, and for a given rate of nutting the centrifugal force tending to throw the bolt off the turret would be much greater, say, four times as great. On the other hand, it is obvious that any desired number of bolt holders, with a corresponding number of small angle indexing steps, may be had by gearing the Geneva stop to the turret shaft instead of having it mounted directly thereon.

The above examples are merely illustrative of the fact that the principle of my novel magnetic bolt holder, as also of my novel magnetic nut chuck, will be found useful in a great variety of relations for handling a variety of articles of magnetic material other than bolts and other than nuts.

The reactions involved in the automatic centering of the nut on the flat surface of the magnetic chuck seem to be complex, and while the utility of this part of my invention

is entirely independent of theory, I may note that the magnet has a widely distributed magnetic field attracting the nut from a distance; that the lines are much more concentrated along the diametric line of separation of the poles of the magnet, and that they are progressively more concentrated toward the periphery of the support surface. It seems important, therefore, that we have means for establishing regions of major, approximately equal magnetic attraction, approximately equidistant from the center of rotation and symmetrically disposed with respect to said axis.

At the periphery, the gap between the poles is rotating at high speed, whereas at the center the speed is zero. Hence, at the periphery the magnetic lines cut into and out of the approaching, non-rotating nut at very high speed, as compared with similar lines near the axis. Anyway, the net result of this seems to be a sort of magnetic vortex generating such reactions that the iron nut is sucked in and centered with respect to the axis before it picks up speed enough to really stick on the magnet surface. The fact that the magnet-engaging face of the nut is crowned may contribute mechanically to the centering effect.

However these things may be, the fact remains that the device operates most effectively as a self feeding and centering chuck and the most obvious reason is that in the position shown in dotted lines in Fig. 6, the nut short-circuits more magnetic lines than in any other position, which is only another way of saying that the magnet attracts it to that position more strongly than to any other and the nut manages to get to that position before it gets stuck on the magnetic surface.

I claim:

1. A nutter for bolts, including a rotary magnetic bolt holder for attracting and holding bolts, in combination with a rotary magnetic nut chuck for attracting, automatically centering and rotating nuts, and means for rotating said bolt holder and presenting the threaded end of a bolt on the holder in register with a nut on the rotating chuck.

2. A nutter for bolts, including a rotary magnetic bolt holder having pairs of cooperating unlike poles adapted to be bridged by a bolt, in combination with a rotary nut chuck for automatically centering and rotating nuts introduced transversely of the axis of rotation of said chuck, and means for rotating said bolt holder and presenting the threaded end of a bolt on the holder in register with a nut on the rotating chuck.

3. A nutter for bolts, including a vertical rotary bolt holder for holding bolts in spaced relation, in combination with a vertical rotary magnetic nut chuck for attracting and automatically centering and rotating nuts, said nut chuck having a flat circular upper

end of substantially the radius required to accommodate the outside dimensions of one of said nuts, means to guide said nuts to the edge of said upper end, and means for presenting the threaded end of a bolt on the holder in register with a nut on the rotating chuck.

4. A nutter for bolts, including a rotary bolt holder for holding bolts in spaced relation, in combination with a rotary magnetic nut chuck for attracting and automatically centering and rotating nuts, said chuck affording a horizontal nut supporting surface comprising segments of different polarities arranged symmetrically with respect to the axis of the nut chuck and of which magnetic lines are close circuited by the nuts, means for rotating the bolt holder step by step and presenting the threaded ends of successive bolts on the holder in register with nuts on the rotating chuck, and means, actuatable by withdrawal of a nut from the chuck with the bolt to which it has been applied, for supplying another nut to the nut chuck.

5. A nutter for bolts, including a rotary turret provided with a plurality of magnetic poles each designed to fit the shank of a bolt, means for indexing the turret through angles corresponding to the spaces between the poles, in combination with a magnetic nut chuck mounted for rotation on an axis aligning with the bolt in one of the indexed positions of the bolts on the turret, means for rotating the chuck at high speed to create a rotating magnetic field attracting, automatically centering and non-positively rotating nuts presented thereto, and means for presenting free bolts and nuts to be attracted by the holder and chuck respectively.

6. A nutter for bolts, including a rotary turret provided with a plurality of pairs of cooperating magnetic poles of unlike polarity, designed to fit the shank of a bolt bridged across them, means for indexing the turret through angles corresponding to the spaces between the poles, in combination with a nut chuck adapted to rotate a nut in a fixed plane and mounted for rotation on an axis aligning with the bolt in one of the indexed positions of the bolts on the turret, means for rotating the chuck at high speed to create a rotating magnetic field adapted to attract, automatically center and non-positively rotate the nuts presented thereto.

7. A nutter for bolts, including a rotary turret provided with a plurality of pairs of cooperating magnetic poles of unlike polarity, designed to fit the shank of a bolt bridged across them, means for indexing the turret through angles corresponding to the spaces between the pairs, in combination with a nut chuck adapted for rotating a nut in a fixed plane and mounted for rotation on an axis aligning with the bolt in one of the indexed positions of the bolts on the tur-

ret, means for rotating the chuck at high speed to create a rotating magnetic field adapted to attract, automatically center and non-positively rotate the nuts presented thereto, and means for supplying bolts and nuts to the holder and chuck respectively.

8. A nutter for bolts, including a rotary turret provided with a plurality of spaced apart bolt holders, means for indexing the 10 turret through angles corresponding to the spaces between the holders, in combination with means, including a magnetic chuck mounted for rotation on an axis aligning with the bolt in one of the indexed positions 15 of the holder, for attracting nuts introduced from the side, automatically centering them on the nut chuck, and rotating them to screw them on corresponding bolts brought to such indexed position.

20 9. A nutter for bolts, including a vertical rotary turret provided with a plurality of spaced apart bolt holders, means for indexing the turret through angles corresponding to the spaces between the holders, in combination 25 with a magnetic nut chuck for attracting, automatically centering and rotating nuts mounted for rotation on a vertical axis, aligning with the bolt in one of the indexed positions of the holder, means for 30 supplying bolts to the holder, means for rotating said magnetic chuck at relatively high speed, and means to present to the surface at the upper end of said magnetic chuck, free, non-rotative nuts to be automatically 35 centered and rotated thereby.

10. A nutter for bolts, including a turret, 40 means for indexing the turret, the turret being provided with a plurality of bolt holders spaced so that each corresponds to an indexed position of the turret, each bolt holder comprising spaced apart magnetic pole pieces of unlike polarity, with notches arranged to have their magnetic lines short-circuited through said shank, and concentric guard 45 segments of non-magnetic material for holding back the bolts at points intermediate the bolt holders, in combination with a rotor having its axis registering with one of the indexed positions of the bolts and adapted 50 to perform operations on each when in said position.

11. A nutter for bolts, including a turret, 55 a Geneva stop for indexing the turret, the turret being provided with a plurality of bolt holders spaced so that each corresponds to an indexed position of the turret, each bolt holder comprising spaced apart magnetic pole pieces of unlike polarity, with 60 notches arranged to have their magnetic lines short-circuited through said shank, and concentric guard segments of non-magnetic material for holding back the bolts at points intermediate the pole pieces, in combination 65 with a magnetic nut chuck having its ver-

tical axis registering with one of the indexed positions of the magnetic bolt holders.

12. A nutter for bolts, including a turret, 70 a Geneva stop for indexing the turret, the turret being provided with a plurality of bolt holders spaced so that each corresponds to an indexed position of the turret, each bolt holder comprising spaced apart magnetic pole pieces of unlike polarity, with 75 notches arranged to have their magnetic lines short-circuited through said shank, and concentric guard segments of non-magnetic material for holding back the bolts at points intermediate the pole pieces, in combination with a magnetic nut chuck having its vertical axis 80 registering with one of the indexed positions of the magnetic bolt holders, and formed with a surface comprising segments which are unlike poles of an electro-magnet, the legs and coils of the magnet being approximately 85 symmetrical with the axis of the chuck, means for rotating said magnet chuck at relatively high speed.

13. A nutter for bolts, including a turret, 90 a Geneva stop for indexing the turret, the turret being provided with a plurality of bolt holders spaced so that each corresponds to an indexed position of the turret, each bolt holder comprising spaced apart magnetic pole pieces of unlike polarity, with 95 notches arranged to have their magnetic lines short-circuited through said shank, and concentric guard segments of non-magnetic material for holding back the bolts at points intermediate the pole pieces, in combination 100 with a magnetic nut chuck having its vertical axis registering with one of the indexed positions of the magnetic bolt holders, and formed with a surface comprising segments which are unlike poles of an electro-magnet, 105 the legs and coils of the magnet being approximately symmetrical with the axis of the chuck, means for rotating said magnet chuck at relatively high speed, and means for presenting to said surface, free, non-rotating nuts to be automatically centered and 110 held thereby.

14. A nutter for bolts, including a turret, a Geneva stop for indexing the turret, the turret being provided with a plurality of bolt 115 holders spaced so that each corresponds to an indexed position of the turret, each bolt holder comprising spaced apart magnetic pole pieces of unlike polarity, with notches arranged to have their magnetic lines short-circuited through said shank, and concentric guard segments of non-magnetic material for holding back the bolts at points intermediate the pole pieces, in combination with a magnetic nut chuck having its vertical axis 120 registering with one of the indexed positions of the magnetic bolt holders, and formed with a surface comprising segments which are unlike poles of an electro-magnet, the legs and coils of the magnet being approximately 125 sym-

- metrical with the axis of the chuck, means for rotating said magnet chuck at relatively high speed and means for presenting to said surface, free, non-rotating nuts to be automatically centered and held thereby; said means including an inclined guideway in which a train of nuts is maintained and an automatic escapement having a trip located outside of the path of travel of the shank of the bolts in the bolt holder, but within the path of travel of nuts that have been screwed thereon. 5 70 75
15. A nutter for bolts, including a turret, a Geneva stop for indexing the turret, the turret being provided with a plurality of bolt holders spaced so that each corresponds to an indexed position of the turret, each bolt holder comprising spaced apart magnetic pole pieces of unlike polarity, with notches arranged to have their magnetic lines short-circuited through said shank, means for presenting successive bolts each with its shank adjacent to and in alignment with successive pairs of bolt holders and a cam wiper adjacent to the bolt supplying means for pressing the shank into the notches, in combination with a magnetic nut chuck having its vertical axis registering with one of the indexed positions of the magnetic bolt holders. 20 80 85 90

16. A nutter for bolts, including a turret, a Geneva stop for indexing the turret, the turret being provided with a plurality of bolt holders spaced so that each corresponds to an indexed position of the turret, each bolt holder comprising spaced apart magnetic pole pieces of unlike polarity, with notches arranged to have their magnetic lines short-circuited through said shank, means for presenting successive bolts each with its shank adjacent to and in alignment with successive pairs of bolt holders, concentric guard segments of non-magnetic material for holding back the bolts at points intermediate the pole pieces, in combination with a magnetic nut chuck having its vertical axis registering with one of the indexed positions of the magnetic bolt holders. 30 35 40 45
17. A nutter for bolts, including a turret, a Geneva stop for indexing the turret, the turret being provided with a plurality of bolt holders spaced so that each corresponds to an indexed position of the turret, each bolt holder comprising spaced apart magnetic pole pieces of unlike polarity, with notches arranged to have their magnetic lines short-circuited through said shank, means for presenting successive bolts each with its shank adjacent to and in alignment with successive pairs of bolt holders, concentric guard segments of non-magnetic material for holding back the bolts at points intermediate the pole pieces, in combination with a magnetic nut chuck having its vertical axis registering with one of the indexed positions of the magnetic bolt holders, and formed with a surface comprising segments which are unlike poles of an electro-magnet, the legs and coils of the magnet being approximately symmetrical with the axis of the chuck, means for rotating said magnet chuck at relatively high speed, and means for presenting to said surface, free, non-rotating nuts to be automatically centered and held thereby, said means including an inclined guideway in which a train of nuts is maintained and an automatic escapement having a trip located outside of the path of travel of the shank of the bolts in the bolt holder, but within the path of travel of nuts that have been screwed thereon. 50 55 60 65 70 75 80 85 90 95 100 105 110 115 120 125 130
18. A nutter for bolts, including a turret, means for indexing the turret, bolt holding means on the turret at positions corresponding to indexed positions of the turret, means for presenting successive bolts of such bolt holding means, in combination with a magnetic nut chuck having its vertical axis registering with one of the indexed positions of the bolt holding means, and formed with a surface comprising segments which are unlike poles of an electro-magnet, the legs and coils of the magnet being approximately symmetrical with the axis of the chuck, means for rotating said magnetic chuck at relatively high speed, and means for presenting to said surface, free, non-rotating nuts to be automatically centered and held thereby, said means including a guideway in which a train of nuts is maintained and an automatic escapement device having a trip located outside of the path of travel of the bolts carried by the turret but within the path of nuts that have been screwed thereon. 135
19. A bolt machine, including a turret on a vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by the shank of a bolt or the like, means for presenting successive bolts, each with its shank adjacent to the periphery of the turret in alignment with successive pairs of bolt holding poles, concentric guard pieces of non-magnetic material for holding back the bolts at points between the notches, in combination with a rotating nut holder having its vertical axis registering with one of the indexed positions of the bolt holders. 140
20. A bolt machine, including a turret on a vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by 145

the shank of a bolt or the like, means for presenting successive bolts, each with its shank adjacent to the periphery of the turret in alignment with successive pairs of bolt holding poles, a cam wiper adjacent the bolt supplying means for pressing the shank into the notches, in combination with a rotating nut holder having its vertical axis registering with one of the indexed positions of the bolt holders.

21. A bolt machine, including a turret on a vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by the shank of a bolt or the like, in combination with a rotor having its axis registering with one of the indexed positions of the bolts and adapted to perform operations on each when in said position.

22. A bolt machine, including a turret on a vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by the shank of a bolt or the like, means for presenting successive bolts, each with its shank adjacent to the periphery of the turret in alignment with successive pairs of bolt holding poles, concentric guard pieces of non-magnetic material for holding back the bolts at points between the notches, in combination with a rotor having its axis registering with one of the indexed positions of the bolts and adapted to perform operations on each when in said position.

23. A bolt machine, including a turret on a vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by the shank of a bolt or the like, means for presenting successive bolts, each with its shank adjacent to the periphery of the turret in alignment with successive pairs of bolt holding poles, a cam wiper adjacent the bolt supplying means for pressing the shank into the notches, in combination with a rotor having its axis registering with one of the indexed positions of the bolts and adapted to perform operations on each when in said position.

24. A bolt machine, including a turret on a

vertical axis, a Geneva stop for indexing the turret, the periphery of the turret being provided with bolt holders parallel with the axis of the turret, spaced apart to correspond with the indexed positions of the turret, each bolt holder comprising a pair of axially spaced magnetic pole pieces of unlike polarity, with notches adapted to be bridged by the shank of a bolt or the like, means for presenting successive bolts, each with its shank adjacent to the periphery of the turret in alignment with successive pairs of bolt holding poles, concentric guard pieces of non-magnetic material for holding back the bolts at points between the notches; a cam wiper adjacent the bolt supplying means for pressing the shank into the notches, in combination with a rotor having its axis registering with one of the indexed positions of the bolts and adapted to perform operations on each when in said position.

25. A carrier for bolts and other elongated articles of magnetic material, including an electro-magnet having axially spaced apart poles formed with cooperating aligned notches adapted to be bridged by the magnetic article, means for moving said carrier to a bolt receiving position and to a bolt delivering position, means for presenting successive bolts to successive sets of aligned notches as the notches are brought to the bolt receiving position, and concentric guards of non-magnetic material between the notches to hold back the bolts.

26. A turret and means for indexing the turret, the turret being provided with bolt holders for holding bolts with their shanks parallel with the axis of the turret, in combination with a rotary magnetic chuck having its axis registering with one of the indexed positions of the bolt holders and formed with a horizontal upper surface comprising two semi-circular segments which are closely confronting poles of an electro-magnet, the legs and coils of the magnet being approximately symmetrical with the axis of the chuck, together with means for rotating said magnetic chuck at relatively high speed.

27. A turret and means for indexing the turret, the turret being provided with bolt holders for holding bolts with their shanks parallel with the axis of the turret, in combination with a rotary magnet chuck having its axis registering with one of the indexed positions of the bolt holders and formed with a horizontal upper surface comprising two semi-circular segments which are closely confronting poles of an electro-magnet, the legs and coils of the magnet being approximately symmetrical with the axis of the chuck, together with means for rotating said magnetic chuck at relatively high speed, and means for presenting to said surface, free, non-rotating nuts to be automatically centered and held thereby.

28. A turret and means for indexing the turret, the turret being provided with bolt holders for holding bolts with their shanks parallel with the axis of the turret, in combination with a rotary magnetic chuck having its axis registering with one of the indexed positions of the bolt holders and formed with a horizontal upper surface comprising two semi-circular segments which are closely confronting poles of an electro-magnet, the legs and coils of the magnet being approximately symmetrical with the axis of the chuck, together with means for rotating said magnetic chuck at relatively high speed, and means for presenting to said surface, free, non-rotating nuts to be automatically centered and held thereby, said means including an inclined guideway in which a train of nuts is maintained and an automatic escapement having a trip located outside of the path of travel of the shank of the bolts in the bolt holder, but within the path of travel of nuts that have been screwed thereon.
29. A turret for carrying elongated articles of magnetic material, including an electro-magnet having as core elements, concentric cylinders each terminating in a radial disc and each disc terminating in a plurality of cooperating, spaced apart poles formed with cooperating aligned notches adapted to be bridged by the magnetic article, windings for oppositely magnetizing the discs and means for relative axial adjustment of the discs to suit the length of the magnetic article, in combination with means for rotating said carrier to an article receiving position and to an article delivering position.
30. A turret for carrying elongated articles of magnetic material, including an electro-magnet having as core elements, concentric cylinders each terminating in a radial disc and each disc terminating in a plurality of cooperating, spaced apart poles formed with cooperating aligned notches adapted to be bridged by the magnetic article, windings on the inner cylinder for oppositely energizing the discs, means for relative axial adjustment of the discs to suit the length of the magnetic article, and the outer cylinder being of sufficient diameter to encompass said winding, in combination with means for rotating said carrier to an article receiving position and to an article delivering position.
31. A nutter for bolts, including a vertical rotary turret provided with spaced bolt holders to hold bolts parallel to the axis of the turret, means for indexing the turret through angles corresponding to the spaces between the holders, in combination with a magnetic nut chuck mounted for rotation on an axis aligning with the bolt in one of the indexed positions of the bolts on the turret, said nut chuck having a flat upper end of sufficient size to accommodate the outside dimensions of one of said nuts, and means to guide said nuts to said flat upper end including a support of non-magnetic material surrounding said flat upper end and with the upper surface of said support forming substantially an extension of the flat upper surface of said chuck.
32. A nutter for bolts, including a magnetic nut chuck adapted to hold a nut non-positively thereon, nut - chuck - actuating means adapted to rotate the chuck at relatively high speeds the poles of the chuck being formed and arranged to create a rotating magnetic field adapted to attract, automatically center and non-positively rotate nuts presented adjacent thereto, and a magnetic bolt holder with poles spaced apart longitudinally of the axis of the chuck and formed with bolt engaging and centering surfaces adapted for non-positively holding a bolt in alignment with the axis of said chuck while permitting movement toward said chuck.
- Signed at Coraopolis, in the county of Allegheny and State of Pennsylvania, this 28th day of December, A. D. 1925.
- WILLIAM B. PEIRCE.
